UNITED STATES PATENT OFFICE.

CHESTER A. BROUGHTON, OF MEDINA, NEW YORK, ASSIGNOR TO A. L. SWETT IRON WORKS, OF MEDINA, NEW YORK.

STAND.

Application filed June 18, 1923. Serial No. 646,194.

To all whom it may concern:

Be it known that I, CHESTER A. BROUGHTON, a citizen of the United States, residing at Medina, in the county of Orleans and

5 State of New York, have invented a new and useful Improvement in Stands, of which the following is a specification.

This invention relates to improvements in stands for range boilers or other articles, 10 and more particularly to stands of the sort having a plurality of angularly adjustable legs adapted to be relatively moved so that their upper ends tilt towards and from each other to engage and support boilers or other 15 articles of different sizes.

The objects of the invention are to provide a stand of this sort which may be inexpensively formed from standard metal bars and sheets, and which has a plurality 20 of leg members and connecting members of like form, each leg and its connecting member being readily detachable as a unit for shipping the stand knocked down; also to provide such stands with improved locking 25 or securing means between the legs and connecting members, which when released, will permit the stand to be easily adjusted to fit different sizes of boilers or other articles. Further objects are to improve stands of 30 this sort in the other respects hereinafter specified.

In the accompanying drawings:

Fig. 1 is a perspective view of my improved boiler stand constructed in accordance with this invention.

Fig. 2 is a sectional plan view thereof.

Fig. 3 is a side elevation, enlarged, of one leg of the stand and its connecting member, showing in full and broken lines two adjustments thereof.

Fig. 4 is a fragmentary vertical section on line 4—4, Fig. 3, enlarged.

The drawings disclose a boiler stand of the tripod form comprising three leg members A spaced apart and adapted to engage at their upper ends, the lower portion or flange X of a range boiler or the like. These legs are rigidly secured to a connecting frame B, comprising connecting bars B' to form a unitary device by securing means adapted to be loosened to permit relative adjustments between the legs and the connecting bars and to be locked to secure said parts in such adjusted positions. It will be 55 understood that the adjustments are made

to move the upper ends of the legs to or from each other so as to engage and support range boilers or other articles of different sizes.

In the preferred embodiment of the invention shown, the legs A are all alike and consist of upright channel bars. These bars may be notched at their upper ends as shown, to receive the flange X and are preferably rounded at the lower ends.

The connecting bars B' are preferably formed of flat bars, and each bar is pivotally connected at b to one of the legs A and at its other end to one of the other bars B' between the ends of that bar, as by a bolt 70 C passing through holes in the bars and secured by a nut c. Each bar is bent or offset laterally adjacent the connecting bolt C, so that together the three bars form a rigid triangular frame or spacing member to hold 75 the legs upright. The inner ends of each bar is also preferably offset at the point of connection with the adjacent bar to lie parallel therewith, and is provided with a hole to receive the bolt C.

The present invention contemplates the provision of improved locking or securing means for holding the legs A and the connecting frame B rigidly together, and which, when loosened, will permit the legs A to be 85 tilted or adjusted relatively to the connecting frame B on the pivots b for the purpose stated.

As shown in the drawings, the legs A are each preferably provided with a brace member D formed of a flat bar having inwardly directed and oppositely inclined arms d and an intermediate part d' arranged in a substantially vertical plane with the ends of the arms d rigidly connected to the leg as 90 by rivets d² on opposite sides of the pivot b. The braces D are directed towards the center of the stand and each is provided in its part d' with a substantially vertical slot E adapted to receive one of the bolts C 100 which connect the bars B' together. The portions of the bars B' which receive the bolts, as before stated, lie parallel to each other and preferably engage opposite faces of the brace member D, and when the nuts 105 are tightened, a rigid and strong stand results. It will be seen that as the slots E are arranged transversely to the bars B, by loosening the nuts, the legs, together with their rigidly attached braces D may be 110

swung and angularly adjusted on the pivots *b* relatively to the frame *B* so as to move the upper ends of the legs nearer to or farther from each other.

5 The construction described is simple and consists of few parts readily produced from standard stock. The legs with their attached braces, permit a stiff, rigid connection between such parts, and the connecting frames, as the locking means for the bars are located at a distance from their pivotal connections so as to prevent or reduce to a minimum any tendency of the parts to twist or move out of their intended position. 10 15 Nevertheless, when loosened, the connection allows the stand to be readily adjusted to fit boilers or other objects of different sizes.

Further, each leg and its companion connecting member forms a substantially flat 20 unit, and when the stand is taken apart for shipment these units will nest compactly together.

I claim as my invention:—

1. In a stand, the combination of a plurality of legs, a connecting frame comprising connecting members secured together and each of which is pivoted to a leg, a brace member on each leg extending inwardly with reference to the stand, securing means for holding each connecting member in definite 25 30 35 relation to a brace to retain the legs in different angular relations to said connecting frame, and means for connecting the end of each connecting member near the pivoted end of said other connecting member.

2. In a stand the combination of a plurality of legs, a connecting frame comprising connecting members secured together and each of which is pivoted to a leg, a brace 40 45 member on each leg extending inwardly with reference to the stand, and securing means for holding each connecting member in definite relation to a brace, to retain the legs in different angular relations to said connecting frame.

3. In a stand the combination of a plurality of legs, each having a brace member extending inwardly with reference to the stand, and a plurality of connecting members, each leg having a connecting member pivoted thereto, said connecting member having its intermediate portion secured to the end of another connecting member and to the brace member of the leg to which said member is pivoted and having its end portion secured to the intermediate portion of a third connecting member.

4. In a stand the combination of a plurality of legs each having a brace member ex-

tending inwardly with reference to the stand, and a plurality of connecting members, each leg having a connecting member pivoted thereto, said connecting member having its intermediate portion secured to the end of another connecting member and to the brace member of the leg to which said member is pivoted and having its end portion secured to the intermediate portion of a third connecting member and to the brace member of another leg.

5. In a stand the combination of a plurality of legs, each having a brace member extending inwardly with reference to the stand and having a slot, a plurality of connecting members, each leg having one end of a connecting member pivoted thereto, said member having its other end connected to another connecting member and to a brace member of another leg by a bolt passing through the slot in said brace member, said slot extending transversely to said connecting member, whereby, when said bolt is loosened, said legs may be angularly adjusted relatively to said connecting members.

6. In a stand the combination of a plurality of legs, a connecting frame comprising connecting members secured together and each of which is pivoted to a leg, a brace member on each leg extending inwardly with reference to the stand, a slot in each brace member extending transversely relatively to said connecting frame, and a bolt in each connecting member arranged to pass through a slot in a brace member and adapted to retain the legs in different angular relations to said connecting frame.

7. In a stand the combination of a plurality of upright legs, a plurality of connecting members each having its outer end connected by a pivot to a leg, a brace rigidly secured to each leg at points on opposite sides of said pivot, said connecting member being connected between its ends to one of said braces, and at its inner end to another brace and another connecting member.

8. In a stand the combination of a plurality of upright legs, a plurality of connecting members each having its outer end connected by a pivot to a leg, a brace rigidly secured to each leg at points on opposite sides of said pivot, each brace having a substantially vertical slot, said connecting member being connected between its ends to one of said braces by a bolt passing through the slot in said brace and the other end of said connecting member being connected to another brace and another connecting member.

CHESTER A. BROUGHTON.
